UNITED STATES PATENT OFFICE.

THOMAS J. STURTEVANT, OF WELLESLEY, MASSACHUSETTS, ASSIGNOR TO STURTEVANT MILL COMPANY, OF BOSTON, MASSACHUSETTS, A CORPORATION OF MASSACHUSETTS.

AIR-SEPARATOR.

1,383,441.

Specification of Letters Patent.

Patented July 5, 1921.

Application filed February 16, 1920. Serial No. 358,983.

To all whom it may concern:

Be it known that I, THOMAS J. STURTEVANT, a citizen of the United States, residing at Wellesley, in the county of Norfolk 5 and State of Massachusetts, have invented an Improvement in Air-Separators, of which the following description, in connection with the accompanying drawings, is a specification, like characters on the drawings representing like parts.

The invention to be hereinafter described relates to air separators for grading materials. Separators of this type are usually provided with a fan for producing an upward current of air through a separating chamber. The materials to be graded are introduced into this upward current of air. The heavier particles or tailings gravitate downward through the upward moving air current, while the lighter particles or fines are carried along with the air current over into a collecting chamber. The tailings and fines are discharged from the separator through outlets communicating with the separating chamber and collecting chamber respectively.

In some cases the materials to be graded are introduced into the separator through the top thereof and gravitate downward to a distributor which throws the particles outward into the path of the upwardly moving air current. In other cases, the materials to be graded are introduced pneumatically into the casing, and are thrown outward into the path of the rising air current.

One of the purposes of the present invention is to provide means positively to feed the materials to be graded into the path of the rising air current. In the present instance of the invention, the feeding-in means is constructed and arranged to conduct the materials from one side of the casing of the separator toward the center thereof.

Another purpose of the invention is to provide means for causing an air current to move upward through the separating chamber and thence downward through a passage and back upward to the separating chamber in a closed circuit, the construction being such that the materials may be delivered into the path of the air current rising in the separating chamber.

Another purpose of the invention is to

provide a rotary distributor which may receive the materials fed into the separator, 51 said distributor being provided with a fan which is rotated by the air current moving upward through the separating chamber. This fan may serve to impart rotation to the distributor to throw the materials outward 60 under the influence of centrifugal force, and also this fan may serve to develop a whirl of the upwardly moving air current, so that the latter will move upward in a long spiral path and the materials may be thrown radially outward and distributed in the path of the upwardly moving air current. Certain of the materials will be thrown farther outward than others by the centrifugal force 65 effect of this whirl depending upon the relative weight or other characteristics of the particles. This will desirably spread the particles and tend to prevent the downward moving heavier particles from impinging upon and pulling down the lighter particles. 70 As a consequence, the efficiency in separating materials is materially increased.

With the aforesaid and other objects in view, the character of the invention will be best understood by reference to the following description of one good form thereof shown in the drawing, wherein a separator embodying the invention is shown in vertical section.

Referring to the drawing, the separator 85 shown therein as one good form of the invention, comprises a casing 1, in the present instance of the invention, including a lower conical wall 3 and an upper conical wall 5 meeting and diverging from their juncture 90 for a purpose to be described. At the lower end of the lower conical wall 3 is a discharge outlet 7 for the lighter particles or fines. The top of the upper conical wall 5 may be provided with a head 9. The casing described may be provided with suitable supporting means, in the present instance, in the form of feet or brackets 11 which may be mounted on beams or other appropriate supports. Mounted within the casing described is an inner casing 13, in the present instance, comprising a lower conical wall 15 and an upper conical wall 17 meeting and diverging from their juncture. This inner casing divides the separator into a separating chamber 19, and a collecting chamber 21.

Suitable means may be provided for causing an air current to move upward through the separating chamber and thence outward into the collecting chamber. This means, in 5 the present instance of the invention, is in the form of a fan 23 comprising a series of vanes 25 secured to and projecting downward from a disk 27 secured to a hub 29 mounted on a vertical shaft 31 projecting 10 upward through and beyond the head 9 of the outer casing. This shaft may be journaled in a lower bearing 33 carried by a sleeve 35 projecting downward from a bearing 37 on a bracket 39 mounted on the head 15 9 of the outer casing. Fast on the upper end of the shaft 31 is a pulley 41 which may be driven by a belt from any suitable source of power. The lower bearing 33 may be lubricated by an oil cup 43 connected by a pipe 20 45 with said bearing. Opposed to the fan 23 is a ring plate 47 mounted on the upper edge of the conical wall 17 of the inner casing and opposed to the disk 27 of said fan.

The construction is such that rotation of 25 the fan will develop an air current upwardly through the separating chamber 19 and whirl the same thence outward between the ring plate 47 and the disk 27 of the fan. This air current will whirl in a spiral path 30 upward through the collecting chamber. Suitable means may be provided for conducting the air current from the collecting chamber back to the lower end of the separating chamber. To accomplish this, in the 35 present instance of the invention, the head 9 of the outer casing may be provided with an opening 49 communicating with a throat 51 which may be connected to a pipe having a horizontal portion 53 projecting outwardly 40 from the casing, a vertical portion 55 projecting downward along the casing toward the bottom thereof, and a curved portion 57 projecting inward toward the casing and meeting an inclined pipe 59 which may project through the casing and be connected with the lower conical wall 15 of the separating chamber.

The construction is such that the fan 23 will draw the air current upwardly through 50 the separating chamber and from the pipe supplying air to this chamber, and as the air is forced by the fan into the collecting chamber, the air in the upper portion of this chamber will flow into the pipe where it 55 will pass to the separating chamber and to the fan again.

As stated, one of the purposes of the invention is to provide means for positively feeding the materials to be graded into the 60 separating chamber. This means, in the present instance of the invention, comprises a hopper 61 communicating with a tube 63 projecting horizontally across the outer casing and secured thereto conveniently at the 65 juncture of the lower conical wall 3 and the

upper conical wall 5 thereof. The tube 63 may have a lateral opening therein communicating with a delivery neck 65 located conveniently centrally of the separating chamber. Suitable feeding means may be 70 mounted in the tube 63, in the present instance, in the form of a screw conveyer 67 on a shaft 69 journaled in bearings 71 and 73 at the opposite ends of the tube 63. Mounted on one end of the shaft 69 is a 75 pulley 75 which may be driven by a belt from any suitable source of power. The construction is such that materials to be graded may be introduced into the hopper 61 and positively fed by the screw conveyer 67 to 80 the neck 65. The materials will pass thence into the separating chamber.

Suitable means may be provided for distributing the materials into the path of the air current rising upward through the separating chamber. This distributor, in the present instance of the invention, comprises a plate or table 77 mounted on the upper end of a stub shaft 79 journaled in a step bearing 81 carried by brackets 83 mounted on and 90 projecting inwardly from the lower conical wall 15 of the inner casing. The step bearing may be lubricated by an oil cup 85 connected by a pipe 87 with said bearing.

Suitable means may be provided for rotating the distributor table 77, in the present instance, this means comprises a fan 89 having vanes 91 secured to the under side of the distributor table 77, and preferably projecting outward therefrom toward the lower 100 conical wall of the inner casing.

The air current rising in the separating chamber will move past the distributor fan 89 and cause the same to rotate. The materials to be graded issuing from the neck 65 105 will drop onto the distributor table, and the rotation thereof will cause the materials to be thrown outward under the influence of centrifugal force into the path of the rising air current. The distributor fan 89 will also 110 produce a whirl of the air current generating a centrifugal force which will further tend to cause the particles to move outward and be distributed into the path of the rising air current. As stated, certain of the 115 particles will move outward farther than others under this influence, depending on the relative weight or other characteristics of the particles, and this separation of the particles will tend to prevent the heavier particles or tailings from impinging upon and pulling downward the lighter particles.

Suitable means may be provided further to contribute to the whirl effect of the air current as it moves upward through the 125 separating chamber. To accomplish this, in the present instance, the pipe 59 leading to the separating chamber may be provided with rifling or spirally disposed ribs 93 projecting inward somewhat from the inner surface 130

of the tube 59. As the air current moves upward through this pipe, it will be caused to move in a spiral or whirling path, so that when the air current reaches the separating 5 chamber, it will enter the same with a pronounced whirl. This whirl will be further enhanced by the rotary motion of the distributor fan 89.

The heavier particles or tailings will 10 gravitate downward through the separating chamber and the pipe 59, and may be delivered therefrom through an outlet 95. This outlet may be provided with a valve or gate 97 which may be pivotally mounted in the 15 outlet 95 and may be urged toward closed position by a weight 99 on an arm 101 projecting from said gate. The construction is such that after a sufficient weight of materials has collected on the gate, it will over- 20 come the counterbalance weight 99 and cause the gate to open to discharge the materials through the outlet 95. Thereupon, the gate will be automatically closed by the weight 99.

Suitable means may be provided to regulate 25 the strength of the air current. This means, in the present instance of the invention, is in the form of a valve 103 mounted in the vertical pipe 55 and provided with a control handle 105.

30 In the operation of the separator, the materials to be graded may be introduced into the hopper 61 and fed by the screw conveyer 67 through the tube 63 to the neck 65. The materials will flow thence onto the 35 rotary distributor table 77, and will be thrown outward into the path of the air current whirling upward through the separating chamber. The heavier particles or tailings will gravitate downward through 40 the rising air current through the pipe 59 and be discharged through the outlet 95 as described. The lighter particles will be whirled with the rising air current upward through the separating chamber and be directed 45 inward by the conical wall 17 toward the axis of the fan. They will move thence outward past the vanes of the fan between the ring plate 47 and the disk 27 of said fan. The lighter particles will be 50 thrown outward under the influence of centrifugal force generated by the whirling air current into the enlarged space in the collecting chamber at the juncture of the lower and upper conical walls of the outer 55 casing. The lighter particles may impinge upon the upper conical wall, and be guided thereby to the lower conical wall, and flow downward along the same and be discharged through the fines outlet 7. The air current 60 may whirl upward through the collecting chamber and be directed toward the opening 49 in the head of the outer casing, and pass thence through the pipes 53, 55, 57, and 59 back to the separating chamber.

65 The fan is desirably located adjacent the

enlarged space between the outer and inner casings afforded by their diverging walls. The lighter particles are thus whirled by the fan outward a substantial distance and have opportunity to leave and gravitate downward through the air current before the latter is directed inward and passes up through the opening at the top of the separator.

It will be understood that the invention 75 is not limited to the specific embodiment shown, and that various deviations may be made therefrom without departing from the spirit and scope of the appended claims.

What is claimed is:—

1. An air separator for grading materials, comprising, in combination, a casing having a separating chamber and a collecting chamber therein, a fan for causing an air current to move upward through the separating chamber into the collecting chamber, a pipe for conducting the air current from the collecting chamber to the separating chamber, means for feeding materials down into the separating chamber, a rotary distributor for receiving the materials from said feed means and delivering the same into the path of the upward moving air current, and a fan rotated by said air current for rotating said distributor. 95

2. An air separator for grading materials, comprising, in combination, a casing having a collecting chamber and a separating chamber, a by-pass conduit leading from the upper portion of the collecting chamber, thence down and up to the lower end of the separating chamber, means for causing an air current to circulate through the conduit, up through the separating chamber to the collecting chamber and from the latter to the conduit, means positively to feed materials to be graded into the separating chamber, and a rotary distributor within the inner chamber for throwing the materials outwardly into the path of the rising air current, the collecting chamber having an outlet to deliver the fines, and the conduit having an outlet for delivering the tailings. 105 110

3. An air separator for grading materials, comprising, in combination, a casing having a collecting chamber and a separating chamber, a by-pass conduit leading from the upper portion of the collecting chamber to the lower end of the separating chamber, means for causing an air current to circulate through the conduit, up through the separating chamber to the collecting chamber and from the latter to the conduit, means to feed materials to be graded into the upper end of the separating chamber, a distributor within the separating chamber beneath the feed means for distributing the materials to be graded into the path of the rising air current, said separating

- chamber being constructed to direct the heavier materials downwardly into the conduit, and means for removing the heavier materials from the conduit.
5. An air separator for grading materials, comprising, in combination, a casing having therein a separating chamber and a collecting chamber, a conduit leading from the upper portion of the collecting chamber, 10 thence downward and upward to the lower end of the separating chamber, means for causing an air current to circulate through the conduit, up through the separating chamber to the collecting chamber and from 15 the latter to the conduit, means to feed materials to be graded into the separating chamber, a rotary distributor within the separating chamber for throwing the materials outwardly into the path of the rising 20 air current, said separating chamber being constructed to direct the heavier particles downwardly into the conduit, and means for removing the heavier particles from the conduit, said collecting chamber having 25 an outlet for delivering the fines therefrom, and said conduit having an outlet for delivering the tailings therefrom.
5. An air separator for grading materials, comprising, in combination, a casing 30 having therein a separating chamber and a collecting chamber, a conduit leading from the upper portion of the collecting chamber, thence down and up to the lower end of the separating chamber, said separating chamber being closed to the collecting chamber at 35 its lower end and communicating therewith at its upper end, means for forcing air from the upper portion of the collecting chamber through the conduit upwardly through the 40 separating chamber, means to feed materials to be graded into the separating chamber, and rotary means for throwing the materials outwardly within the separating chamber into the path of the rising air current, said collecting chamber having an outlet 45 to deliver the fines therefrom, and said conduit having an outlet to deliver the tailings therefrom.
6. An air separator for grading materials, comprising, in combination, an outer 50 casing having a lower conical wall and an upper conical wall meeting and diverging from their juncture, an inner casing within the outer casing and having a lower conical wall and an upper conical wall meeting and diverging from their juncture, said casing forming a separating chamber within the inner casing and a collecting chamber surrounding the separating chamber, means to 55 cause an air current to circulate upward through said separating chamber into said collecting chamber, and means to feed materials to be graded down into the separating chamber in the path of the air current moving upwardly therein.
7. An air separator for grading materials, comprising, in combination, a casing having a separating chamber and a collecting chamber therein, a conduit leading from the upper end of the collecting chamber to the 70 lower end of the separating chamber, a fan for causing air current to circulate through said separating chamber, collecting chamber and conduit, means to feed materials to be graded into the separating chamber, and a rotary distributor for receiving materials and whirling the same outward into the separating chamber, said distributor having a fan for rotating the same driven by the air current moving upward through the separating chamber.
8. An air separator for grading materials, comprising, in combination, a separating chamber, means to introduce materials to be graded into said separating chamber, means for causing an air current to move upwardly in the separating chamber, a rotary distributor having a material supporting area of substantial extent for receiving the materials thereon and throwing the same outward under the influence of centrifugal force, and means operatively connected with the rotary distributor and driven by the upward movement of the air current to rotate the distributor.
9. An air separator for grading materials, comprising, in combination, an outer casing, an inner casing dividing the outer casing into a separating chamber and a collecting chamber, means for causing air current to move upward through said separating chamber, a bearing mounted in said separating chamber, a rotary distributor mounted in said bearing, a fan for rotating said distributor and actuated by the air current moving upward in said separating chamber, and means to feed the materials to be graded to said rotary distributor, that they may be whirled by the latter outwardly in the separating chamber in the path of the air current moving upwardly therein.
10. An air separator for grading materials, comprising, in combination, a separating chamber, means for causing an air current to move upwardly therein, a rotary distributor comprising a plate mounted in said separating chamber, and having a material supporting area, a fan for rotating said table actuated by the air current moving upward in said separating chamber, and means to feed materials to be graded onto said table.
11. An air separator for grading materials, comprising, in combination, a separating chamber and a collecting chamber, a pipe leading from the upper end of said collecting chamber to the lower end of said separating chamber, means for causing an air current to circulate through said separating chamber, collecting chamber and said pipe, the latter having spiral ribs projecting in

- wardly therefrom for causing the air to whirl as it enters the separating chamber, a rotary distributer mounted in said chamber, a fan for rotating said distributer actuated by the air current moving upward in said separating chamber, and means for feeding materials to be graded into said separating chamber to said distributer, that they may be thrown outward by the latter into the separating chamber under the influence of centrifugal force.
12. An air separator for grading materials, comprising, in combination, a casing having a separating chamber and a collecting chamber therein, a fan located above said separating chamber a substantial distance beneath the upper end of the collecting chamber, a vertical shaft carrying said fan projecting downward through the top of the casing, a rotary distributer mounted in said separating chamber, a conduit for conducting material from the collecting chamber back into the separating chamber, and means to feed materials to be graded into said separating chamber beneath said fan and above said distributer.
13. An air separator for grading materials, comprising, in combination, a casing having a separating chamber and a collecting chamber therein, a pipe leading from the upper end of the collecting chamber around the casing and upward to the lower end of the separating chamber, said casing having an outlet for delivering fines therefrom, and said pipe having an outlet for delivering tailings therefrom, means for causing an air current to circulate through said separating chamber, collecting chamber and pipe in closed circuit, an air driven rotary distributer in said separating chamber, and means to feed materials to be graded to said rotary distributer.

In testimony whereof, I have signed my name to this specification.

THOMAS J. STURTEVANT.
